[57] CLAIM

The ornamental design for a suspended fluorescent lighting fixture, as shown and described.

DESCRIPTION

FIG. 1 is a front, left end perspective view of a suspended fluorescent lighting fixture showing my new design, the rear and right end view being a mirror image;

FIG. 2 is a fragmentary front, left end perspective view thereof on an enlarged scale;

FIG. 3 is a bottom plan view thereof;

FIG. 4 is a fragmentary front elevational view thereof on an enlarged scale;

FIG. 5 is a front, left end perspective view of a second embodiment of my new design, the rear and right end view being a mirror image;

FIG. 6 is a fragmentary front elevational view thereof on an enlarged scale; and,

FIG. 7 is a bottom plan view thereof.

The fixture is fragmentarily shown in FIGS. 1, 2, 4 and 6 for convenience of illustration.

FIG. 3

FIG. 4

FIG. 6

FIG. 5

FIG. 7
